UNITED STATES PATENT OFFICE.

JOSEPH RUNDECKER, OF WEST STRATFORD, CONNECTICUT.

DESIGN FOR AN ORNAMENTAL STAND.

SPECIFICATION forming part of Design No. 18,640, dated September 25, 1888.

Application filed August 24, 1888. Serial No. 283,683. Term of patent 7 years.

To all whom it may concern:

Be it known that I, JOSEPH RUNDECKER, a citizen of the United States, residing at West Stratford, in the county of Fairfield and State 5 of Connecticut, have invented and produced a new and original Design for Ornamental Stands; and I do hereby declare the following to be a full, clear, and exact description of the invention, such as will enable others skilled in 10 the art to which it appertains to make and use the same.

In the accompanying drawings, forming a part of this specification, Figure 1 is a perspective illustrating my design; and Fig. 2, a 15 similar view, showing especially the horn in the background extending in an opposite direction to that shown at Fig. 1, these two views being deemed necessary to fully illustrate my design.

20 The leading feature of my design consists in the representation of a hoof for the base of the

stand, while secondary to this feature is the representation of a horn rising in the background above said hoof.

A is the hoof, and B the horn.

25 The appearance of my design is not materially changed by extending the horn in opposite directions, as shown in the drawings.

What I claim is—

30 The design for an ornamental stand herein shown and described, the same comprising the representation of a hoof for the base of the stand and the representation of a horn rising above the hoof in the background, as shown and described.

35 In testimony whereof I affix my signature in presence of two witnesses.

JOSEPH RUNDECKER.
